1 Claim

ABSTRACT OF THE DISCLOSURE

A first serial connection comprises a first resistor, a first transistor and a first load. A second serial connection comprises a second load, a second transistor, a second resistor and a third load. The first serial connection is connected parallel to the second serial connection. A current of a magnitude proportional to the magnitude of the current in the first load is obtained in the second and third loads.

BACKGROUND OF THE INVENTION

This invention relates to an electric current converting circuit and more particularly to an electric current converting circuit in a direct current operational circuit in which one of the terminals of a plurality of loads or operational circuits is connected to the fixed potential of a power source.

SUMMARY OF THE INVENTION

In the invention of subject application, a first serial circuit comprised of a first resistor, a first transistor and a first load is connected across a constant current source and a second serial circuit comprised of a second load, a second transistor, a second resistor and a third load is connected across a current source. When the voltage across the base electrode and the emitter electrode of the first transistor is made substantially equal to the voltage across the base electrode and the emitter electrode of the second transistor, the current in the second load and the third load can be made proportional to the current in the first load.

Therefore, the object of this invention is to obtain an electric current converting circuit which is capable of supplying current to the above loads simultaneously.

BRIEF DESCRIPTION OF THE DRAWING

FIGS. 1 and 2 are the connection diagrams showing the basic form of the electric current converting circuit of this invention, and

FIGS. 3 through 6 are the connection diagrams showing embodiments of the electric current converting circuit of this invention.

DESCRIPTION OF THE PREFERRED EMBODIMENTS

In FIG. 1, the emitter of a PNP type transistor Q_1 is connected to a terminal 1 and the base of an NPN type transistor Q_2 through a resistor R_1 and the emitter of the transistor Q_2 is connected to a terminal 4 and the base of the transistor Q_1 through a resistor R_2 .

The collector of the transistor Q_1 is connected to the negative terminal of a constant current power source 11 and the negative terminal of a power source E_2 through a terminal 2 and a load or an operational circuit Z_1 , and the positive terminal of constant current power source 11, is connected to terminal 1.

The collector of the transistor Q_2 is connected to the positive terminal of a power source E_1 through a terminal 3 and a load or an operational circuit Z_2 , and the negative

2

terminal of the power source E_1 is connected to the positive terminal of the power source E_2 and a load or a terminal of an operational circuit Z_3 .

Another terminal of the load Z_3 is connected to terminal 4, and a joint between the emitter of the transistor Q_2 and the resistor R_2 forms a terminal 5.

The circuit surrounded by terminals 1, 2, 3 and 4 is named a four-terminal network N. The resistors R_1 and R_2 function to determine the conversion characteristics.

In the circuit shown in FIG. 1, if it is assumed that constant current power source 11 generates a current I_1 in the direction shown in the figure, a voltage V across terminals 1 and 4 becomes as follows:

$$V = I_1 R_1 + V_{be1}$$

where:

R_1 = resistance of resistor R_1 .

V_{be1} = voltage across base and emitter of transistor Q_1 .

The transistors Q_1 and Q_2 have both high gains and the base current is smaller than the collector current; accordingly, it is possible to assume that the collector current of the transistor Q_1 is equal to the current I_1 .

If the current supplied from the battery E_1 to the circuit consisting of the load Z_2 , the transistor Q_2 , the resistor R_2 and the load Z_3 is represented by a current I_2 , the voltage V across terminals 1 and 4 is shown by the following formula.

$$V = V_{be2} + I_2 R_2$$

where:

V_{be2} = voltage across base and emitter of transistor Q_2 .

R_2 = resistance of resistor R_2 .

As it is possible to make the difference between the voltages V_{be1} and V_{be2} extremely small, the following relation can be obtained.

$$I_1 R_1 = I_2 R_2$$

By changing the above equation, it is obtained that

$$I_2 = \frac{R_1}{R_2} I_1$$

The above equation shows that the current I_2 which is obtained by multiplying the constant current I_1 , flowing through the load Z_1 by the multiplication factor R_1/R_2 flows through the loads Z_2 and Z_3 .

The direction connecting the base-emitter junction of the transistors Q_1 and Q_2 is arranged in such a direction that the above voltages V_{be1} and V_{be2} compensate each other against the heat of their own generation and the variations of ambient temperature. Consequently, the variations in the voltages V_{be1} and V_{be2} due to the change of temperature cancel each other and no error will take place in the circuit.

Thus, the connection of two transistors of mutually different polarities makes it possible to reduce the conversion errors compared with the case where only one transistor is used.

As stated above, from across terminals 1 and 4 and from across terminals 5 and 4 can be taken out respectively different voltage outputs $I_1 R_1 + V_{be1}$ and $I_2 R_2$.

Instead of the transistors Q_1 and Q_2 , if a composite transistor circuit consisting of a combination of two or more transistors is employed, the conversion accuracy can be improved as the input impedance becomes high and the current amplification factor increases. In addition, as it is possible to make the collector current small in the first stage of the composite transistor circuit, the compensation for the voltage across the base and emitter against the self-generated heat and ambient temperature variation will be extremely improved.

FIG. 2 shows the method to connect the various components in case the polarities of constant current power source 11 in FIG. 1 are reversed.

FIG. 3 shows a connection diagram in case the power source E_2 is inserted between terminal 2 and the load Z_1 in FIG. 1. This type of connection is employed when it is more desirable to supply power separately from an inverter as the power source E_2 in such a common direct current power source system as impresses a direct current 24 volt voltage to individual instruments. 5

FIG. 4 shows an arrangement where the loads Z_4 and Z_5 are connected in parallel in addition between terminals 4 and 5 in FIG. 1. 10

FIG. 5 shows a connecting method capable of taking out a current output in parallel using a transistor which does not especially compensate for the voltage across the base and emitter in FIG. 1. 15

FIG. 6 shows a connecting method capable of increasing current load by connecting in series-parallel a plurality of the four-terminal networks in FIG. 1. 15

As stated above, the advantages of this invention are that in the current conversion circuit of this invention, a high conversion accuracy can be obtained, it is possible to simplify the power supply composition for the amplifier to be used as a load and the whole operational circuit, and it is possible to supply current simultaneously to a maximum of three loads in the basic conversion circuit. 20

What is claimed is:

1. An electric current converting circuit comprising: 25

a pair of transistors having mutually different polarities,
a pair of resistors connecting the emitters of the respective transistors to the bases of the other transistors, a constant current power source and a first load connected in series with a circuit composed of one of the transistors and one of the resistors, a second load, a current power source and a third load connected in series with a circuit composed of the other of the transistors and the other of the resistors, and a separate current power source connecting the first load to the third load.
